UNITED STATES PATENT OFFICE.

HENRY L. KUENZLI, OF NEVADA, OHIO.

WATER-FILTER.

1,136,538.

Specification of Letters Patent. Patented Apr. 20, 1915.

Application filed July 14, 1914. Serial No. 850,981.

To all whom it may concern:

Be it known that I, HENRY L. KUENZLI, a citizen of the United States, and a resident of Nevada, in the county of Wyandot and State of Ohio, have invented a new and useful Improvement in Water-Filters, of which the following is a specification.

My invention is an improvement in water filters, and has for its object to provide a device of the character specified, for interpolation in the pipes leading to cisterns or other receptacles for rain water, and wherein mechanism is provided, arranged within the length of the pipe and between the receiving and the delivery ends for filtering the water during its passage and for removing sediment of all character from the water, and wherein the said removing means is so arranged that the action of the water coming on to the said means will clean the sediment from the cleaning means and deliver it outside of the pipe.

A further object is to provide a removable screen that may be taken out and replaced or renewed, and to provide mechanism in connection with the screen and the filter for preventing loss of water through the opening for the discharge of the impurities by splashing or by capillary attraction.

In the drawings:—Figure 1 is a front view of an improved filter, Fig. 2 is a section on the line 2—2 of Fig. 3. Fig. 3 is an enlarged section at right angles to Fig. 2, Fig. 4 is a section on the line 4—4 of Fig. 3, Fig. 5 is a perspective view of a portion of the screen supporting frame, and Fig. 6 is an enlarged section of the lower end of the screen.

The present embodiment of the invention comprises a casing 1 of substantially rectangular cross-section, having a top 2 and a bottom 3. The bottom is hopper shaped, as shown, for preventing the damming up of water in the bottom of the filter, and the outlet of the bottom is provided with a nipple or pipe section 4, for engaging the supply pipe of the cistern or other receptacle. The top 2 is provided with a nipple or pipe section 5, with which one of the arms of an elbow 6 is engaged. The pipe section or nipple 5 and the elbow are annularly beaded as indicated at 7, and the beads fit within each other to provide for a rotatable connection of the elbow with the casing, and to prevent disengagement of the elbow and the casing. The arms of the elbow are at an

obtuse angle with respect to each other, the arrangement being such that when the arm engaged with the pipe section or nipple 5 is perpendicular the other arm will be inclined 60 upwardly at about the angle of the down spout or conductor pipe of a building.

In the present embodiment of the invention the body 1 of the casing is made from a single sheet of sheet material and the joint is at the front as indicated at 8. At this point an opening 9 is provided, the said opening being encircled by a reinforcing wire frame 10. The frame 10 is substantially rectangular, and a portion of the material of the casing is bent over or beaded around the frame as shown, to hold the frame in place and to provide a rigid wall at every side of the opening.

The screen comprises a substantially rectangular frame, consisting of side members 11, an upper end member 12, and a lower end member 13. Each of the side members near its lower end is doubled backward upon itself as indicated at 14, and is then bent 75 forwardly and downwardly as indicated at 15, to a connection with the end member 13. A covering 16 of perforate material, as for instance, wire mesh of suitable size, is supported by the frame. The covering 16 is 80 on the front of the frame when in place, and the said covering extends downward in a double fold between the doubled-over portions 14 of the side members and thence forwardly along the portion 15 to the end member 13, to which the lower end of the covering is connected.

It will be noted from an inspection of Fig. 6, that the doubled-over portions of the screen are rigidly connected at the upper 95 end of the portions 15, the said connection being by means of solder or the like, and extending the full width of the screen. The rear face of this solid portion it will be noted is flush with the rear face of the covering of the screen, so that no impediment is offered to the flow of water down past the solid portion.

It will be noticed that each of the portions 15 of the frame is arched or curved 105 slightly longitudinally, the concavity being upward, and the covering 16 follows the shape of the said portion. The solid portion 17 before mentioned is flush or continuous with the curve of the members 15 at its upper side, so that a continuous surface is 110 formed on the front of the screen along the

upper face of the solid portion 17 and on that portion of the screen connected to the members 15. The solid portion performs several functions, first as a reinforcement to 5 the screen at this point, second as a dividing member for separating the water from impurities at this point and constraining the water to pass downward in the filter while permitting the impurities to pass forward 10 over the apron formed by that portion of the screen connected with the portion 15 of the side members.

At each end the end member 13 is provided with a depending pin 18, and when 15 the screen is in place, these pins 18 engage outside of the lower end member of the frame 10 to lock the screen from rearward movement at this point. The upper end of the screen fits beneath a deflecting plate, 20 consisting of a portion 19, fitting the rear face of the casing 1, and secured thereto by means of bolts and nuts 20, and a portion 21 which extends outwardly and downwardly from the rear wall of the casing over 25 the upper end of the screen. This portion 21 of the deflecting plate is spaced apart from the rear wall a sufficient distance to permit the upper end of the screen to slip upwardly behind the said portion during 30 the placing of the screen.

It will be noticed that the screen frame is of a width corresponding approximately to the width of the casing 1 and that it may be inserted into the casing and removed therefrom through the opening 9. When in place however, the side members 11 of the screen fit against the side walls of the casing. The screen is inserted by passing the upper end through the opening 9 and upwardly beneath the lower end of the portion 21 of 35 the deflecting plate, and the screen is pushed up until the lower end thereof, that is, the connection between the bodies of the side members 11 and the doubled-over portions 40 14 will pass over the lower end members of the frame 10. The screen is then permitted to slip downward until the portions 15 will rest upon the lower end of the opening 9, and with the pins 18 engaging outside of the 45 said frame 10.

To brace the screen when in place a rod 22 is arranged transversely of the casing, the said rod being passed through the side walls as shown in Fig. 4, and having its ends headed as indicated at 23, or in any other desired manner. The rod 22 is at about the center of the screen.

A plate 24 is arranged in the casing above the screen, the upper end of the plate having a bearing 25, which encircles a rod 26 arranged transversely of the casing, near the upper end and slightly in front of the center of the casing. The plate hangs vertically, and the lower end thereof is curved 60 slightly toward the screen as indicated at 65

27. This lower end is slightly below the center of the screen, and the free lower end of the plate is spaced apart forwardly from the screen. The plate hangs below the upper end of the opening 9 a little distance, as will be evident from an inspection of Fig. 3, and the said plate is a splash plate and guard to prevent splashing of the water through the opening 9. It will be noted that this plate hangs directly in front of the point where the water coming through the nipple 5 will strike the screen, and it will prevent splashing of the water from any cause. By spacing the free edge of the splash plate away from the screen 80 slightly, there will be no hindrance to the free passage of the impurities down on the outer face of the screen.

In practice, the improved filter is placed in the down spout of the building in vertical position, and it will be evident that the water discharged through the nipple 5 will strike the screen, and the water will pass through directly, leaving the impurities on the upper face of the screen. Some of the water will pass down under the screen, following the screen, and the solid portion 17 at the junction of the body of the screen with the apron or deflecting portion will deflect this water downward into the casing, 90 and will also deflect the impurities over the apron and outside of the casing.

The elbow 6 being pivotally connected with the casing, may be turned in any direction so that the improved filter may be 100 placed without regard to the direction from which the inclined portion of the pipe comes, since it is obvious that the elbow may be swung to either side. The elbow prevents the flow of water from striking directly on 105 the screen. The elbow changes the direction of the water, and slows the flow, thus preventing injury to the screen. Were the inlet straight and attached to a down spout of considerable length, even a small solid 110 body in the water would strike the screen with considerable force and might cause considerable damage. With the elbow however, this cannot occur.

The hopper bottom strengthens the filter 115 at this point, and insures the thorough drainage of the water from the filter. It will be evident that since the screens are removable, interchangeable screens may be used of different degrees of fineness. The 120 filter is entirely sanitary, every part being accessible, and it is self-cleaning, the flowing water throwing the impurities out of the casing.

I claim:—

1. A device of the character specified, adapted to be interposed within the length of a supply pipe for a cistern or other receptacle for rain water, and comprising a 130 casing of approximately rectangular cross

section having an opening in one wall intermediate the ends of the body and of the width of the casing, and having a reinforcing frame at the opening, said casing having 5 an inlet at its upper end and an outlet at its lower end, a screen arranged transversely of the body at the opening and in inclined position, said screen comprising a substantially rectangular open frame consisting of 10 side members and end members, and a covering of perforate material, the side members and the covering being doubled back upon themselves near their lower ends and being then bent forwardly, the forwardly 15 bent portion extending through the opening and resting on the casing at the lower end of the opening with the doubled portion engaging the inner surface of the casing, the screen having depending pins engaging out- 20 side of the casing at the opening and a solid portion extending between the side members at the junction of the doubled back portions of the body of the screen, said solid portion having its rear face flush with the rear face 25 of the screen and its upper face connecting the front face of the body of the screen with the upper face of the forwardly bent portion, the screen inclining downwardly toward the opening, a deflecting plate detach- 30 ably connected with the inner face of the casing at the upper end of the screen and extending over the said upper end, and a splash plate mounted to swing at its upper end and depending toward the screen below the up- 35 per end of the opening.

2. A device of the character specified, adapted to be interposed within the length of a supply pipe for a cistern or other receptacle for rain water, and comprising a 40 casing having an opening in its front wall intermediate the ends thereof and of the width of the casing, said casing having an inlet at its upper end and an outlet at its lower end, a screen arranged transversely of the casing and inclining upwardly toward its upper end, said screen having at its lower end a laterally bent portion extending through the opening and resting on the casing at the lower end of the opening, the 45 screen also having a portion depending within the casing at the opening, and said screen having a solid portion at the junction of the portions with the body of the screen, a deflecting plate connected with the casing and 50 extending over the upper end of the screen, and a splash plate suspended from the casing toward the upper face of the screen, the lower end of the plate being below the upper end of the opening and being spaced apart from the screen.

3. A device of the character specified, adapted to be interposed within the length of a supply pipe for a cistern or other receptacle for rain water, and comprising a casing having an opening in its front wall in-

termediate the ends thereof and of the width of the casing, said casing having an inlet at its upper end and an outlet at its lower end, a screen arranged transversely of the casing and inclining upwardly toward its upper end, said screen having at its lower end a laterally bent portion extending through the opening and resting on the casing at the lower end of the opening, the screen also having a portion depending within the casing at the opening, and said screen having a solid portion at the junction of the portions with the body of the screen, and a deflecting plate connected with the casing and extending over the upper end of the screen.

4. A device of the character specified, adapted to be interposed within the length of a supply pipe for a cistern or other receptacle for rain water, and comprising a 85 casing having an opening in its front wall intermediate the ends thereof and of the width of the casing, said casing having an inlet at its upper end and an outlet at its lower end, a screen arranged transversely of the casing and inclining upwardly toward its upper end, said screen having at its lower end a laterally bent portion extending through the opening and resting on the casing at the lower end of the opening, the 90 screen also having a portion depending within the casing at the opening, and said screen having a solid portion at the junction of the portions with the body of the screen.

5. A device of the character specified, comprising a casing having an opening in its front wall and having an inlet at its top and an outlet at its bottom, a screen arranged transversely of the casing and inclining downwardly and forwardly, said screen having a portion extending laterally forward at an angle to the body of the screen and resting on the casing at the lower end of the opening and having a portion 105 depending within the casing at the opening, a deflecting plate connected with the casing at the top of the screen, and a splash plate depending in front of the screen below the center thereof and spaced apart from 110 the screen.

6. A device of the character specified, comprising a casing having an opening in its front wall and having an inlet at its top and an outlet at its bottom, a screen arranged transversely of the casing and inclining downwardly and forwardly, said screen having a portion extending laterally forward at an angle to the body of the screen and resting on the casing at the lower 120 end of the opening, and having a portion depending within the casing at the opening.

7. A device of the character specified, comprising a casing adapted to be arranged in vertical position and having openings at 130

- its ends and a screen arranged transversely of the casing, the casing having an opening in one wall and the screen having an angular portion extending through the opening and a portion depending within the opening, a splash plate depending between the screen and the upper end of the opening, and a deflecting plate for the upper end of the screen.
- 10 8. A device of the character specified, comprising a casing adapted to be arranged in vertical position and having openings at its ends and a screen arranged transversely of the casing, the casing having an opening in one wall and the screen having an angular portion extending through the opening and a portion depending within the

opening, and a splashing plate depending between the screen and the upper end of the opening.

20

9. A device of the character specified, comprising a casing adapted to be arranged in vertical position and having openings at its ends and a screen arranged transversely of the casing, the casing having an opening in one wall and the screen having an angular portion extending through the opening, and portion depending within the opening.
